Res. 1511

David Hathaway of Troy, New York.

Assignor to

Fulmer, Warren & Co. of same place.

Letters Patent No 1511 dated Jan. 7 1862.

The schedule referred to in these Letters Patent and making part of the same.

to and whom it may concern:

Be it known that I, David Hathaway, of the City of Troy, in the County of Rensselaer, and State of New York, have invented or provided a new and original ornamental Design for Cook Stove Plates, and I do hereby declare that the following is a full and exact description of my said invention or production, reference being had to the annexed photographic drawing of stove plates having my said ornamental design.

Dec 15/11

The distinguishing characteristic of my said ornamental design for cook stove plates is, the arrangement, upon the right angled doors or plates A, B and C, of the rectangular, plain and beaded-like compound moulding d, along the inside border, the raised rectangular panels e, having circularly recessed corners f, and the concave border moulding g; and the minor rounded oblong panels h, surrounded by the correspondingly shaped beaded-like and plain compound moulding i, all as shown by the annexed photograph.

What I claim as new and of my invention or production and desire to secure by Letters Patent, is cook stove plates ornamented as above described.
